WILLIAM R. PETERSON AND NELLIE R. DORRINGTON, OF CHICAGO, ILLINOIS, ASSIGNEES
TO ST. REGIS PAPER COMPANY, OF NEW YORK, N. Y., A CORPORATION OF NEW
YORK

BAG FILLING AND DISCHARGING APPARATUS

Application filed December 4, 1929. Serial No. 411,422.

This invention relates to apparatus for filling bags and discharging the filled bags. More particularly, it relates to apparatus adapted to fill valve bags, automatically stop the filling operation when the desired weight of material has been filled into a bag and thereafter automatically discharge the bag and prepare the apparatus for receiving an empty bag. The object of the invention is to provide an apparatus of the character described which will work accurately and with certainty and will require a minimum of effort on the part of the operator. Details of the invention will appear as the description proceeds.

In the accompanying drawings forming a part of this specification, Figure 1 is a vertical section through one embodiment of the invention, parts being broken away for purpose of illustration; Fig. 2 is an enlarged section similar to Fig. 1, but showing details of the tripping apparatus; Fig. 3 is a section showing a part of the mechanism disclosed in Fig. 2 together with some added details 25 and showing the parts in their position just as the automatic means are operating to begin the discharge of a bag; Fig. 4 is a section similar to Fig. 3, but showing the parts in their position after the bag is discharged; Fig. 5 is a detailed view showing the mechanism for initiating the filling operation.

In the apparatus shown, there is a casing 10 within which there is a shaft 11 driving a propeller, not shown, for discharging material through an outlet opening 12. Across the casing adjacent the outlet opening there is provided a slot 13 in which there operates a gate 14 having therein an opening 15 adapted to register with the filling opening 12 when the gate is raised. The lower end of the gate is connected by a spring 16 to a bracket 17 and the spring constantly tends to lower the gate so as to place the opening in the position in which it is shown in Figs. 3 to 5, inclusive. Above the upper end of the gate there is a lever 18, and the upper end of the gate is connected by a flexible strap 19 to the end of the lever, the lever being provided with an arcuate portion 20 described about the fulcrum 21 of the lever as a center and constantly tan-

gent to the plane of the gate, so that the pull of the lever upon the gate is always directly endwise of the gate.

The upper end 22 of lever 18 is adapted to engage a wear plate 23 of a latch 24. Latch 24 is constantly urged by a spring 25 towards vertical position, while a weight 26 attached to the latch substantially overcomes the tension of the spring when the main arm of the latch is in a vertical position.

The lower end of the latch, when in a vertical position, is adapted to engage a wear plate 28 on a trigger 29 pivoted at 30 to a fixed bracket. Trigger 29 is constantly urged upward by a spring 31 attached to a fixed pin 32, while the upward movement of the latch is limited adjustably by a set screw 33. The outer end of the trigger is engaged and depressed, as will be described later, by a set screw 35 in a lug 36 mounted upon a bag-carrying frame 37. The upper end of frame 37 is connected to a casing by a link 38, while the lower end of frame 37 rests upon a forked scale beam 39. Mounted on frame 37 there is a cross piece 40 having therein an opening 41 adapted to register with discharge opening 12. A carrier 42 pivoted on the cross piece at 43 is provided with a spout 44 having one end in alignment with opening 41 and having its other end adapted to enter the valve of a bag. Carrier 42 is provided with an arm 45, and a spring 46 connected to this arm and to the frame normally holds the carrier with spout 44 raised, as shown in Figs. 1 to 3.

A bag clamp 47 is pivoted at 48 upon frame 37 above spout 44. Clamp 47 is provided with a lug 49 which is connected by a spring 50 with cross piece 40 and normally holds the clamp down towards the spout. A pin 52 on clamp 47 works in a slot 53 on a catch 54 pivoted at 55 on cross piece 40. Catch 54 is provided with a notch 56 adapted to engage a lug 57 on the upper portion of carrier 42 and hold the carrier locked in raised position. Extending upward from latch 47 there is an arm 58 carrying a roller 59 adapted to be engaged by a member 60 pivoted upon lever 18 and normally held by a spring 61 in the position in which it is

shown in the drawings. A lug 62 extending upward from latch 47 is provided with a set screw 63 adapted to engage member 36 and limit the movement of clamp 47 to the right, 5 as shown in the drawings.

A bottom support 64 is provided with 10 pivots 65 adapted to engage notches 66 in downward extensions of frame 37. Bottom 64 is also provided with pins 67 which may be placed in any of a series of holes 68 in 15 links 69 pivoted at 70 to the outer ends of arms 45.

Above the hopper of the discharge device 20 there is mounted a shaft 71. This may be connected to an agitating device for assisting in feeding material to the hopper, as is well known in the art. Shaft 71 is provided with an eccentric 72 connected by a link 73 to a pivot 74 on an arm 75 of a rock shaft 25 76. Another arm 77 on rock shaft 76 is pivoted to a lifting member 78. A lifting hook 79 is pivoted at 80 to member 78, and is provided with a notch 81 adapted to engage a pin 82 on lever 18. A spring 83 normally 30 presses lifting hook 79 to the position in which it is shown in Figs. 1, 2 and 4. A link 84 pivoted at 85 to a fixed bracket carries a roller 86 adapted to engage hook member 79 and press it into operative position. 35 A spring 87 connects link 84 with a pin 88 directly above pivot 85 and tends to hold link 84 in a sliding position on either side of the vertical to which it is moved. Link 84 is provided with a pin 89 working in a slot 90 in the end of an arm 91 operated by handle 92. A set screw 93 through a lug 94 attached to arm 91 limits the movement of that arm to the left, as shown in Fig. 2. A set screw 95 limits the movement of arm 40 91 to the right, as shown in Fig. 5.

The operation of the device is as follows. Presuming the parts to be in the position in which they are shown in Figs. 1 and 2, a bag, not shown, will be in position upon the filling spout so as to receive material discharged through the filling opening and through spout 44 into the bag. When sufficient material has been fed into the bag to overbalance the scale beam so as to result in a downward movement of frame 37, set screw 35 engages the end of trigger 29 and releases latch 24. Thereupon, spring 16 pulls the gate downward to its closed position, as shown in Fig. 3, swinging the upper end of lever 18 to the right and forcing latch 24 outward to the position in which it is shown in Fig. 3.

When member 60 is moved downward to the position in which it is shown in Fig. 3, it engages roller 59 and oscillates clamp 47 60 to release it from the bag and also through pin and slot connection, 52, 53, raises catch 54 to release carrier 42. Thereupon, the weight of the bag upon spout 44 and bottom 64 overcomes spring 46 and moves the bottom 65 downward to slanting position, and also the

filling spout 44 to the position in which it is shown in Fig. 4. Thereupon, the bag slides off of the bottom and spout. Thereafter, spring 46 immediately raises carrier 42, spout 44 and bottom 64 to the position in 70 which they are shown in Figs. 1 to 3. With the parts in this position, an empty bag may be placed upon the spout. Thereafter, the operator depresses handle 92 thus swinging link 84 to the right until roller 86 contacts the lower end of member 79. Thereupon, spring 87 tends to continue the movement of the link until spring 83 is overcome and the hook is positioned beneath pin 82. It will be readily understood that as shaft 71 is rotating constantly member 78 continues to be reciprocated vertically. Upon the next upward movement of members 78 and 79 after the shifting of handle 92, the engagement of hook 81 with pin 82 raises lever 18 and opens 80 the gate. If desired, when the bag is placed upon the spout, the outer end of member 60 may be depressed and the clamp tightened to place catch 54 in holding position. When lever 18 moves upward, member 60 will oscillate on its pivot and not interfere with the holding of the clamp and catch. It will be understood that frame 37 along with clamp 47, arm 58 and roller 59 are in slightly lowered position when the trip is actuated to 90 close the gate and immediately after the bag slips off of the spout and bottom frame 37 returns upward to its normal position which is normally sufficient to raise it above member 60. Thereupon, spring 50 swings the clamp 100 towards clamping position until stopped by set screw 63. This prevents the catch from moving so far as to interfere with the proper return of carrier 42 to its filling position. The upward movement of lever 18 engages handle 92 and thereby swings links 84 to the position in which it is shown in Figs. 1 and 2. The parts are thereby returned to the original position in which they are shown in Fig. 1 and the operation is repeated. 110

What is claimed is:

1. In apparatus for filling and discharging valve bags, a discharging device having a discharge orifice, a gate controlling the orifice, said orifice being approximately horizontal and the gate closing by moving upward and outward across said orifice, means for opening and closing the gate, a lever connected with the gate, a latch adapted to engage an arm on said lever and hold the gate open, a frame having a spout thereon adapted to enter the valve of a bag, weighing means upon which said frame is mounted, and a lug on said frame in position to engage the latch when the frame is in its raised position and to release the latch when the frame is lowered. 115

2. In apparatus for filling and discharging valve bags, a discharging device having 120

a discharge orifice, a gate controlling the orifice, said orifice being approximately horizontal and the gate closing by moving upward and outward across said orifice, a 5 spring constantly tending to close said gate, manual means for opening the gate, a lever connected with the gate, a latch adapted to engage an arm on said lever and hold the gate open, a frame having a spout thereon 10 adapted to enter the valve of a bag, weighing means upon which said frame is mounted, and a lug on said frame in position to engage the latch when the frame is in its raised position and to release the latch when the frame 15 is lowered, the spout being pivoted at its end next to said orifice.

3. In apparatus for filling and discharging valve bags, a discharging device having a discharge orifice, a gate controlling the 20 orifice, said orifice being approximately horizontal and the gate closing by moving upward and outward across said orifice, a spring constantly tending to close said gate, manual means for opening the gate, a lever 25 connected with the gate, a latch adapted to engage an arm on said lever and hold the gate open, a frame having a spout thereon adapted to enter the valve of a bag, weighing means upon which said frame is mounted, a 30 lug on said frame in position to engage the latch when the frame is in its raised position and to release the latch when the frame is lowered, the spout being pivoted at its end next to said orifice, a catch for normally 35 holding said spout in horizontal position, and means connected with the gate for releasing said latch when the gate is closed.

4. Apparatus for filling and discharging bags comprising a casing having a discharge orifice therethrough, said orifice being substantially horizontal, a gate adapted to move upward and outward across said orifice and close the same, a frame connected to said gate, a lever connected to the upper end of said frame, a spring adapted to normally close said gate, manual means for opening the gate, a latch adapted to engage an arm on said lever and hold the gate open, a bag supporting frame, weighing means upon which 45 said frame is mounted, a pivoted spout on said frame adapted to enter the valve of a bag, a pivoted support on said frame connected to said spout, a spring tending to raise the spout and support to horizontal position 50 and strong enough to raise them with an empty bag thereon but not strong enough to support the weight of a filled bag, a catch adapted to maintain the spout and support in horizontal position, means on the frame 55 for engaging said latch while the frame is in raised position and releasing the latch when the frame is lowered in response to the weight of the filled bag, and a lug on said lever 60 adapted to engage said catch and release the 65 spout and support when the gate is closed.

In testimony whereof I have hereunto signed my name to this specification.

WILLIAM R. PETERSON.
